UNITED STATES PATENT OFFICE.

ARCHIBALD C. BEEMAN, OF OKLAHOMA, OKLAHOMA.

EXTENSION FOR HANDLES.

1,389,477.

Specification of Letters Patent. Patented Aug. 30, 1921.

Application filed October 20, 1919. Serial No. 331,820.

To all whom it may concern:

Be it known that I, ARCHIBALD C. BEEMAN, a citizen of the United States, residing at Oklahoma city, in the county of Oklahoma and State of Oklahoma, have invented certain new and useful Improvements in Extensions for Handles, of which the following is a specification, reference being had to the accompanying drawings.

10 The handle of the lock on the average automobile door is too small to be easily grasped and too short to afford the leverage required to unlock the door.

15 The object, therefore, of the invention is to provide a suitable hand-hold and extension for handles of this kind.

Figure 1 of the drawings is a fragmental perspective view showing the door of a "Ford" automobile and the short handle 20 that usually projects from the door to release the lock.

Fig. 2 is a reproduction of Fig. 1, but with the improved hand-hold applied to the handle.

25 Fig. 3 is a perspective view of an inverted U-shaped filler used in the hand-hold.

Fig. 4 is a side elevation of the hand-hold, partly in section.

30 Fig. 5 is a side elevation of the handle, with the hand-hold in place.

Like characters of reference designate like parts in all the figures.

The numeral 10 designates an automobile door, and 11 the handle which commonly 35 projects outward from the lock of the door.

The hand-hold 12, which may be of any suitable material, has a square hole 13 extending from its lower end well upward toward its upper end to receive the handle 11; 40 and if desired the extreme upper end of the

hand-hold may be widened into a convenient finger-hold 14.

To hold the hand-hold 12 in place on the handle 11, an inverted substantially U-shaped filler 15 of elastic strap material is 45 provided, this filler having its arms 16 corrugated as shown.

In putting the hand-hold 12 on the handle 11, the filler 15 is first set straddle of the handle, and the hand-hold is then driven 50 forcibly down over the handle and filler.

As the hand-hold is forced downward, it clamps the arms 16 of the filler 15 flatly against the handle 11 in opposition to the elastic force of their corrugations, so that 55 said filler is brought into permanent and forcible frictional engagement with said handle and hand-hold and thereby holds the latter in place.

The following is claimed:

1. A handle extension comprising a hand-hold disconnectible from the handle and detachably engageable therewith, and a resilient filler insertible in the hand-hold and frictionally engaging the walls thereof and 60 adapted to frictionally engage over the end of the handle, the end of the hand-hold being widened to form a finger hold. 65

2. A handle extension comprising a hand-hold disconnectible from and detachably engageable over the end of the handle, and a resilient filler insertible in the hand-hold and frictionally engaging the walls thereof and adapted to frictionally engage over the 70 end of the handle, the end of the hand-hold being widened to form a finger hold offset 75 from the hand-hold.

Witness my hand this 8th day of October.

ARCHIBALD C. BEEMAN.
